RADIAL PUMP HOUSING OR THE LIKE

William F. Wanner, Minneapolis, Minn.

Application December 16, 1957, Serial No. 48,906

Term of patent 14 years

(Cl. D65—1)

Figure 1 is a side elevational view of the instant invention;

Figure 2 is an elevational view from a direction opposite from that shown in Figure 1; and

Figure 3 is an elevational view as seen from the left of Figure 1.

The essential features of my design reside in those portions shown in full lines.

I claim:

The ornamental design for a radial pump housing or the like, substantially as shown and described.
